(57) **CLAIM**

I claim the ornamental design for a tire, as shown and described.

DESCRIPTION

FIG. 1 is a perspective view of a tire showing my present design;

FIG. 2 is an enlarged view showing a portion of the tire as indicated in FIG. 1 thereof;

FIG. 3 is a front view thereof;

FIG. 4 is an enlarged view showing a portion of the tire as indicated in FIG. 3 thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

In the drawings, the cut lines shown in FIGS. 1 & 3 indicate the areas shown as enlarged views in FIGS. 2 & 4. The broken lines depict environmental subject matter only and form no part of the claimed design.
